JOHN P. McDONOUGH, OF ST. LOUIS, MISSOURI, ASSIGNOR OF ONE-HALF TO L. A. RAGAN,
OF ST. LOUIS, MISSOURI.

STOVE AND RANGE CONSTRUCTION.

977,417.

Specification of Letters Patent. Patented Nov. 29, 1910.

Application filed April 8, 1910. Serial No. 554,196.

To all whom it may concern:

Be it known that I, JOHN P. McDONOUGH, a citizen of the United States, residing at St. Louis, State of Missouri, have 5 invented certain new and useful Improvements in Stove and Range Constructions, of which the following is a full, clear, and exact description, reference being had to the accompanying drawings, forming a part 10 hereof.

My invention has relation to improvements in stove and range constructions; and it consists in the novel details more fully set forth in the specification and pointed out in 15 the claim.

In the drawings, Figure 1 is a side elevation of a conventional stove or house range, the wall of the stove being removed to show the interior, and the parts being shown in 20 section along the plane of removal of said wall, the said figure showing my invention applied to said stove; and Fig. 2 is a horizontal section taken below the stove-top on the line 2—2 of Fig. 1.

25 The object of my invention is to substitute for the grate and ash-sifter in the prevailing forms of heating and cooking stoves and ranges, an upper burning water-tube grate and a lower burning grate, both being 30 located in the same fire-box compartment, the ends of the water-tubes terminating in headers (either in the form of boxes as shown, or their equivalents) exposed to the heat of the combustion products, the lower 35 grate intercepting whatever fuel drops from the upper grate and not previously consumed thereon.

A further object is to so dispose the grate 40 surfaces as to cause the draft to pass from the compartment above the upper grate through said upper grate and into the compartment between the grates, the draft from the lower-burning grate being upward and rearward whereby the products ultimately 45 pass into and through the stove flues into the exit flue in the usual way.

A further object is to effect perfect combustion of the fuel, producing practically no smoke, insuring cleanliness and a high heating 50 efficiency.

The water-tube grate and its respective headers are in circuit with a water-tank, the contents of which is kept heated by the circulation of the water between it and the

headers and tubes, so that a constant supply 55 of hot water may always be on hand.

The advantages of the invention will be best apparent from a detailed description thereof, which is as follows:—Referring to the drawings, S represents a conventional 60 form of stove or range (though the invention is applicable to any form of heating furnace), in which the fire-box is represented by F, and the ash-receptacle by A. Separating the ash-receptacle from the fire-box 65 is an ordinary upward burning grate G to which atmospheric air may be admitted through the valve-controlled openings of doors D, D''. Above the door D is a front header 1 which is connected by means of the 70 upwardly and rearwardly inclined water-tubes 2 to an inner header 1' located within the fire-box and spaced from the rear wall thereof as shown. Tapping the upper portion of the inner header 1' is a circulating 75 pipe a which discharges into the upper end of a hot-water tank T placed adjacent to, and extending above the stove, the return from the tank entering the upper portion of the header 1 through the circulating or return pipe a'. Sections of these pipes a, a', 80 are disposed alongside the stove and below the stove-top, thereby being out of the way and not interfering with the movements of the person working about the stove. Access 85 to the water-tubes 2 which form the upper and main grate for the fuel may be had through a door D' placed between the stove-top and the header 1, air being admitted into the space above the water-grate through 90 valve-controlled openings of said door D' as well understood in the art. The stove is provided with a damper-controlled exit flue 95 E to which lead the usual stove flues or passages f as well understood, no description of these being necessary.

Whatever fuel is not consumed on the upper grate formed by the water-tubes 2 will drop onto the lower grate G and there be thoroughly consumed. As seen from the 100 arrows in Fig. 1, the upper grate, which divides the fire-box into two superposed inter-communicating compartments (one above the upper grate, and the other between the grates) is a downward burning grate, 105 whereas the bottom grate G is an upward burning grate. The air drawn through the upper grate carries with it unconsumed

products of combustion, and as these must not only pass through the incandescent carbon on the upper grate, but must mix more or less with air and the combustion products 5 passing upward and rearward from the bottom grate G, it follows that all the products will be practically consumed and no smoke result. So that we not only have a stove which completely burns all available 10 carbon and other combustible elements of the fuel, but serves to heat a maximum quantity of water to be used for domestic or other purposes. Owing to the complete consumption 15 of the fuel, a minimum quantity of ash will result, no smoke or soot will deposit in the stove flues, and a clean fire is at all times assured. The invention is not limited to any special design of stove, range or furnace.

20 Having described my invention, what I claim is:—

In combination with a stove having a bottom ash receptacle and a fire-box between said receptacle and stove top, a bottom grate 25 separating the fire-box from the ash receptacle, a rearwardly and upwardly inclined water-tube grate mounted across the fire-

box a suitable distance above the bottom grate and dividing the fire-box into two superposed sections, an outer header forming a 30 wall for the upper fire-box section and discharging into the bottoms of the water-tubes, an inner header engaging the stove-top and forming a tight joint therewith and spaced a suitable distance from the rear 35 wall of the fire-box and from the bottom grate and receiving the discharges from the inner upper ends of the water-tubes, a water-tank located outside, and extending above, the stove, circulating pipes leading from the 40 upper portions of the respective headers and communicating with the top and bottom of the water-tank, doors above and below the outer header leading to the respective fire-box sections opposite thereto, an exit 45 flue, and flues in the stove connecting said flue with the rear of the fire-box.

In testimony whereof I affix my signature in presence of two witnesses.

JOHN P. McDONOUGH.
